F. A. WESCOTT.
AUTOMOBILE INDICATOR.
APPLICATION FILED DEC. 8, 1916.

1,279,055.

Patented Sept. 17, 1918.

UNITED STATES PATENT OFFICE.

FRED A. WESCOTT, OF CORNING, NEW YORK, ASSIGNOR TO THE WESCOTT-BANKER SIGNAL CO., INC.

AUTOMOBILE-INDICATOR.

1,279,055.

Specification of Letters Patent. Patented Sept. 17, 1918.

Application filed December 8, 1916. Serial No. 135,834.

To all whom it may concern:

Be it known that I, FRED A. WESCOTT, a citizen of the United States, residing at Corning, in the county of Steuben and State 5 of New York, have invented certain new and useful Improvements in Automobile-Indicators, of which the following is a specification.

The present invention relates to combined course indicators and license tag illuminators for automobiles.

The main object of the invention resides in the novel construction of the invention which is characterized by its simplicity permitting the device to be cheaply manufactured, the object also contemplating such a device which is efficient and effective for its purpose.

A feature of the invention resides in the provision of a casing so constructed as to permit a compact assemblment of various indicating means which will designate the course to be taken by the vehicle and which will permit the application of the usual license tag in a manner which will illuminate the entire face of the tag in order that the characters thereon may be clearly distinguished for a great distance. It is to be understood that the invention may be applied either on the front or rear of a vehicle, or both.

The indicating means in this invention comprise a plurality of characters which may be separately illuminated at the will of the operator.

Other features of the invention will later appear from the following detailed description and from the drawings which illustrate the invention:

40. Figure 1 is a front elevation of the invention illustrating the application of the usual license tag thereto;

Fig. 2 is a rear view of the invention with the back plate removed, and

45. Fig. 3 is a view taken substantially on the line 3—3 of Fig. 1.

Like characters denote similar like parts throughout the specification and drawing.

With particular reference to the drawings 50. 1 represents a casing adapted to house and support the indicating means and comprises a front and back plate 2 and 3, respectively, held in spaced relation by the side and top walls of the casing, preferably formed by 55 single strips 4 of metal. It will be seen

from the drawings that the plates 2 and 3, have their side portions cut away so as to converge upwardly, thereby reducing the size of the device and rendering it more compact as well as reducing the cost of 60 manufacture. The lower portions of the front and back plates 2 and 3 are bent inwardly, at substantially right angles, to about as indicated at 7 and are then extended downwardly in juxtaposition to form a 65 flange 8 to be presently more in detail referred to. It will be noted, however, that the plate 3 is only extended inwardly at 6 for a comparatively short distance with respect to the inward extensions 5 of the plate 70 2. The lower edge of the plate 3 is upturned over the lower edge of the plate 2 as indicated at 9 so as to embrace or form a seat for the lower edge of the plate 2. The casing, thus provided, is divided into the 75 various compartments in which are disposed illuminating means for purposes which will be presently understood.

The partition 10 extends horizontally across the casing 1 dividing it into upper 80 and lower compartments and preferably consists of a metallic strip secured at its front and side edges to the front and side walls of the casing, respectively by any suitable means such as solder, or the like. The rear 85 edge of the partition 10 is bent laterally thereto to engage with the rear wall 3 in order to prevent the light in the upper compartment from penetrating into the lower compartment. The front plate 2 has the 90 portion thereof opposite the upper compartment formed with an elongated horizontal opening 11 therein covered by a translucent plate 12 secured in position by the screws or other fastening means 13. The plate 12 95 may have suitable characters placed on its inner face which will be visible from the outside of the casing when the upper compartment is illuminated, however, it is preferred to place a stencil 14, of a shape corresponding to said plate 12, in juxtaposition with the inner surface of the plate and also held in position by the fastening means 13. An electric socket 15 is disposed in the upper compartment and mounted on the 100 partition 10. The lower compartment of the casing is divided by vertical partitions 16 and 17 which provide a central compartment c and end compartments e. The central compartment c is illuminated by an 110

electric bulb which is fitted in the socket 18 disposed and mounted therein, and the front plate 2 has an elongated opening 19 therein, opposite said compartment *e* and directly under the opening 11 the opening 19 being covered by colored translucent plate 20, preferably red, to provide a tail lamp for the vehicle. The plate 20 is held in place by the clips 21 secured at the inner side 10 edges of the opening 19.

The end compartments *e* are each illuminated by suitable electric lamps which are received in the sockets 22 disposed and mounted therein and the front plate 2 at 15 portions opposite these compartments is formed with the circular openings 23 and 24. The opening 23 is covered by a translucent plate 25 which is, preferably backed by a stencil 26 which has suitable characters 20 to indicate that the course to be taken by the vehicle will be to the "right"; and the opening 24 is likewise covered by a translucent plate 27 backed by a stencil 28 which will indicate that the course of the vehicle will 25 be to the "left". In the present instance the stencils bear the characters "R" and "L", however, it is to be understood that an arrow or any suitable character which will serve the purpose may be provided on 30 the stencil. The plates 25 and 27 and their respective stencils are held in suitable position by means such as the screws 29. It will be noticed that from the peculiar shape of the casing that the end compartments *e*, *e*, 35 in which are lodged the course indicators, are disposed at the lower extremities of the casing and at one side of the tail light and the stop signal, it being understood that the stencil 14 bears suitable characters which 40 indicate that the vehicle has stopped.

The casing 1 may be applied to the vehicle in any suitable manner and the sockets 15, 18 and 22 are connected in any suitable manner to a source of electrical energy carried 45 by the vehicle which will permit the lamps to be individually illuminated by the manipulation of a suitable switch carried at a convenient place on the vehicle.

The invention further contemplates the 50 adaptation of the usual license tag to the signal box in a manner that the characters will be illuminated to such a degree as to be readily distinguished at a comparatively great distance. To accomplish this purpose 55 the depending flange 8 is inclined to form an acute angle relative to the extension 5 of the plate 2, as shown in Fig. 3, and has the license tag secured thereto by suitable means such as the screws 30 which extend 60 through the flange, it being noted that the screws 30 also securely hold the lower ends of the plates 1 and 2 into position. The license tag *L* is, by virtue of the inclination of the flange 8, at a suitable angle out of 65 the vertical as to have its front or char-

actered surface entirely illuminated by the light reflected through an opening 31 formed in the bottom of the central compartment *c* and through said extension 5, this opening 31 being elongated and extending the 70 full length of said compartment. A glass plate 32 covers the opening 31 and is held in position by the clips 33 and 34, the former being held in position between the abutting ends 7 of the plates 1 and 2 and the latter 75 being preferably stamped from the extension 5. Arcuate reflectors 35 are disposed in the ends of the central compartment *c* so that the light in the compartment may be reflected to cover the entire surface of the 80 license tag from end to end, and in a manner which will be readily understood. These reflectors 35 are held in position by solder, screws or other suitable means as may be found convenient. The characterized surface 85 and license plate *L* so held and illuminated will be easily distinguished and read at a distance of 150 feet or more according to the atmospheric conditions.

From the above it will be noted that a 90 combined indicator, and license tag holding and illuminating device of a novel construction is devised, the principal features of which are the simplicity of construction and the few parts necessary for its completion. The parts of the device may be readily stamped and assembled without great cost, however, producing a durable device which is efficient and desirable for its purpose. It 95 is preferred that the indicating means in the present device are not visible until the various compartments are each illuminated so that the light will penetrate the openings in the stencil.

The above specifically describes the preferred embodiment of the invention, however, this construction may be changed and any other arrangement and organization of parts may be resorted to which does not depart from the legitimate scope of the appended claims.

What is claimed is:—

1. An automobile signal, which comprises a casing having approximately the shape of a trapezium, the upper wall of which is made from a single piece of metal with flanges formed on its edges, a front wall having spaced openings of different sizes and shapes and having a bent lower portion terminating in a downwardly depending flange, two of said openings being in vertical alinement, one of the latter openings being provided with a translucent plate having characters thereon, the other of the openings being provided with a translucent colored plate to serve as a tail light, a partition secured horizontally in the casing and provided on its rear edge with a vertical flange having spaced holes therein, a back wall for the casing having its upper edge

engaged with one of the flanges of the top, said wall also being adapted to form a portion of the bottom wall of the casing and is provided with an opening and a downwardly depending flange having a recurved edge to coöperate with and to receive the downwardly depending flange of the front wall, said front and back wall flanges serving as a license plate attachment, spaced 5

10 vertical partitions serving as reflectors interposed and secured between the horizontal partition and the bottom wall, said vertical partitions producing a central compartment with smaller compartments adjoining, each

15 one of the remaining openings in the front wall being disposed in front of a smaller compartment, means for illuminating the several compartments and their openings, and spaced curved reflectors in the central

20 compartment to direct light through the opening in the bottom wall.

2. An automobile signal, which comprises a casing having approximately the shape of a trapezium, the top wall being made of a 25 single piece having a portion adapted to lie parallel to and spaced from the bottom, and connected to the bottom wall by sloping portions, the edges of the top wall being bent at right angles to form flanges, front 30 and back plates serving as walls, each plate having the approximate shape of a trapezium with their upper and sloping edges adapted to engage with the flanges of the top wall, an L-shaped partition extending longitudinally of the casing and having its ends 35 in contact with and secured to the sloping portions of the top wall, the longer portion of the partition extending transversely of the casing and subdividing the casing into com-

partments, the edge of the longer portion of the partition being in contact with the inner surface of the front wall, the shorter portion of the partition extending vertically and in contact with the back wall, means for securing said shorter portion to said back 40 wall, said back wall being bent inwardly 45 and forming a portion of the bottom wall of the casing, said bottom wall portion having a downwardly portion terminating in a recurved end, the front wall of the casing 50 having a bent portion adapted to form the remainder of the bottom wall which is provided with a downwardly projecting flange whose free end is adapted to seat in the recurved end of the downwardly projecting 55 portion of the back wall, spaced vertical partitions extending between the bottom wall and the longitudinal partition to form compartments, the center one of which is larger 60 than the others, the front wall being provided with a plurality of openings having translucent material serving as closures therefor, each of said openings being in one wall of each of the compartments, and the bottom wall portion of the front wall being 65 also provided with an opening having a translucent closure, a lamp socket in each of the compartments, and reflecting means in the lower central compartment serving to direct the light rays outward and also downward 70 toward the projecting flanges.

In testimony whereof I affix my signature in presence of two witnesses.

FRED A. WESCOTT.
